POURING SPOUT CONTAINER

John M. Hothersall, Brooklyn, N. Y., assignor to
American Can Company, New York, N. Y., a
corporation of New Jersey

Application June 23, 1936, Serial No. 86,873
(Cl. 221—11)

6 Claims.

The present invention relates to a container or can having a rotatable hinge cover pouring spout unit which in non-pouring or closed position is below the rim or edge of the can and which may be rotated to extend beyond the can rim or edge so as to bring the spout into pouring position, the invention having particular reference to holding the hinged cover of the spout closed and locked against opening when the spout is in non-pouring position.

The present invention is an improvement on the article disclosed in my pending application on Pouring spout container filed in the United States Patent Office on September 25, 1934, under Serial Number 745,471 Patent No. 2,075,848, April 6, 1937.

An object of the invention is the provision of a sealed can for liquids having a confined, movable hinge cover pouring spout which, after the can is opened, may be positioned for pouring where it directs the flow of liquid issuing therefrom, and which may be moved into non-pouring or closed position where the hinge cover is locked against opening at which time the spout is utilized as a reclosure for resealing the can.

Numerous other objects and advantages of the invention will be apparent as it is better understood from the following description, which, taken in connection with the accompanying drawing, discloses a preferred embodiment thereof.

Referring to the drawing:

Figure 1 is a perspective view of the upper end of a can and a pouring spout embodying the instant invention, the view showing the pouring spout in non-pouring and locked position;

Fig. 2 is a fragmentary top plan view of the can and pouring spout shown in Fig. 1 illustrating the spout in pouring position with its cover open, the cover being partly broken away;

Fig. 3 is an enlarged transverse section taken through the spout and the adjacent sealed can parts as viewed substantially along the line 3—3 in Fig. 1;

Fig. 4 is a view similar to Fig. 3 and of the same parts, showing the can after opening and with the pouring spout in pouring position, the view being taken substantially along the line 4—4 in Fig. 2; and

Fig. 5 is a sectional detail taken through the spout and viewing the underside of its hinged cover, the view being taken substantially along the line 5—5 in Fig. 4.

A preferred embodiment of the present invention as disclosed in the drawing comprises a metal can 11 (Fig. 1) adapted to contain a liquid and this can has an imperforate cover member 12 for closing it. The cover member illustrated is preferably formed with a central panel 13 surrounded by an upstanding rim 14 (see also Fig. 3) which is secured to the can in any suitable manner such

as by being curled over at 15 into tight engagement with a curled edge 16 of the can. Bendable cover lugs 17 or their equivalent engage under the curled edge of the can and hold the cover against displacement. A gasket 18 is interposed between the cover curl 15 and the curled edge 16 of the can and provides a hermetic seal between can and cover.

Provision is made for opening the can by breaking through the cover wall when dispensing of the liquid contents of the can is desired. The dispensing of the liquid is effected by way of a pouring spout 21 which is associated with the cover. The spout is located in a depression 22 formed in the cover panel 13, the depression having sloping side walls 23 and an inclined floor 24.

A cylindrical recessed socket 25 is provided in the floor 24 of the depression 22 and this socket forms a seat for holding the pouring spout 21. The socket is formed with depending side walls 26 and a bottom wall 27 which is parallel with the inclined floor of the depression. It is in the bottom wall 27 of this socket that the breaking through of the cover wall is effected to allow for the dispensing of the liquid contents of the can.

A portion of the bottom wall 27 of the recessed socket 25 is weakened by being cut through or scored (Fig. 3) with lines 28, 29 which enclose areas 31, 32. These enclosed areas when the can is to be opened may be pressed in by a blunt instrument or suitable opening tool in the usual manner. This opening action breaks through the lines 28, 29 and bends the metal by pushing the enclosed areas into the can as shown in Fig. 4. The breaking through of the bottom wall in this manner provides a pouring opening 33 and a vent opening 34.

The pouring spout 21 is rotatably mounted in the recessed socket 25 and is provided with an annular body 41 having a flared or inclined wall 40 section 42 which seats against the depending side wall 26 of the socket, the wall 26 also being inclined toward and engaging the flared wall spout section 42 in order to confine the spout within the socket. The bottom edge of the wall section 45 42 is turned in horizontally as at 43 and this provides a smooth seating corner edge which facilitates easy turning of the spout in the socket.

At one side the annular body 41 is laterally extended in a trough-like pouring lip 45 which, when the spout is in non-pouring position as shown in Fig. 3, is confined within the depression 22 of the can cover 12 and the entire spout is then below the cover rim 14.

An elongated spout cover 46 is hinged at one end to the spout body 41 by means of a pair of spaced hinge lugs 47 which engage in slots 48 cut out of the spout body. The slots are disposed adjacent the top edge of the spout body and between this edge and the slots is a por-

tion 49 of the body which serves as a pintle around which the lugs are bent and on which the cover is hinged.

The opposite end of the spout cover is preferably formed with a bent catch part 52 which is adapted to snap over the end of the spout lip 45 when the cover is closed on the spout. The spout cover is so shaped and dimensioned as to completely enclose the upper or open edge of the spout. Figs. 1 and 3 illustrate the spout cover 46 in spout closing position and it will be observed that the cover as well as the spout lip is below the top edge of the can. Figs. 2 and 4 show the cover in raised position where it uncovers the spout lip. The spout is rotated on the inclined floor of the depression from its closed position, in order to bring the spout lip over the can rim 14 and into its pouring position.

20 Provision is made for positively holding the spout cover 46 in this raised position so that it will not obstruct the free flow of liquid discharging through the spout during emptying of the can. This is effected by a coiled torsion spring 54 which is wrapped around a pintle strip 55 (Fig. 5) set off by an opening 56 formed in the spout body 41 adjacent the edge thereof, this opening being between the spaced hinge slots 48. One end of the spring engages against the inside of the spout body while the other end engages against the inside of the spout cover as shown in Fig. 5.

The torsional stress in the spring tends to make it uncoil and exerts the proper pressure 35 against its ends to hold the spout cover in open position as illustrated in Figs. 2 and 4. As previously mentioned this allows for free pouring action of the liquid contents of the can, which pouring action is brought about by tilting the filled can in the usual manner. The liquid passing out through the pouring opening 33 and by way of the spout lip 45 is discharged from the end of the lip in a controlled stream (Fig. 4).

45 When only a part of the contents of the can is dispensed and it is desired to reseal the can, the spout cover may be used as a reclosure. After such a dispensing action the cover is easily snapped closed over the spout lip 45 and the spout is then rotated into its non-pouring position within the depression 22 as it was before opening the can.

50 Provision is made for locking the cover in this closed position so that it cannot be accidentally opened. For this purpose the sloping wall 23 of the depression 22 is bent inwardly in a substantially vertical locking wall 51 (Fig. 3) which is engaged by the catch part 52 of the spout cover when the spout is in non-pouring position. The cover when in this position cannot be raised, hence it reseals the can. This locking feature is particularly advantageous in holding the spout cover closed during shipment and storage of the can even before it is received by the ultimate consumer.

55 It is thought that the invention and many of its attendant advantages will be understood from the foregoing description, and it will be apparent that various changes may be made in the form, construction and arrangement of the parts without departing from the spirit and scope of the invention or sacrificing all of its material advantages, the form hereinbefore described being merely a preferred embodiment thereof.

I claim:

1. A container comprising a wall having a depression therein, a pouring spout rotatably disposed in said depression for dispensing the contents of the container, said pouring spout having a non-pouring position and also having a pouring position, a cover on said spout for closing the same, and means in a wall of said depression for locking said cover against opening when the pouring spout is in non-pouring position.

2. A container comprising a wall having a depression therein, a pouring spout rotatably disposed in said depression for dispensing the contents of the container, said pouring spout having a non-pouring position and also having a pouring position, a cover hinged at one side of said spout, and means in a wall of said depression for engaging the free side of said cover for locking said cover against opening when the pouring spout is in non-pouring position.

3. A container comprising a wall having a depression therein, a pouring spout rotatably disposed in said depression for dispensing the contents of the container, said pouring spout having a non-pouring position and also having a pouring position, a hinged cover mounted on said spout, elements for holding said hinged cover open and out of the way of a stream issuing from the pouring spout when the latter is in pouring position, and means in a wall of said depression for locking said cover against opening when the pouring spout is in non-pouring position.

4. A container comprising a wall having a depression therein, a portion of the wall within the depression having a weakened section adapted to be perforated to open the container, a pouring spout rotatably and non-removably disposed in said depression and surrounding said weakened section for dispensing the contents of the container, said pouring spout having a non-pouring position, a cover on said spout for closing over the spout and in which position it effects a closure for the container after it has been opened, and means in a wall of said depression for locking said cover against opening when the pouring spout is in non-pouring position.

5. A container comprising a wall having an inclined depression surrounded by a projecting rim, a pouring spout rotatably disposed in said depression, said pouring spout having a non-pouring position where it is entirely disposed below the said projecting rim and also having a pouring position where it extends over said rim, a cover on said spout for closing over the spout thereby effecting a reclosure for the container, and means in a wall of said depression for engaging said cover and locking the same against opening when the pouring spout is in non-pouring position.

6. A container comprising a wall having a depression therein, a pouring spout rotatably disposed in said depression for dispensing the contents of the container, said pouring spout having a non-pouring position and also having a pouring position, a hinged cover mounted on said spout, and an inwardly projecting wall section formed in a wall of said depression and engageable by said hinged cover when the latter is closed and the spout is in non-pouring position for locking the cover against opening.
